SECTIONAL CONCRETE DRY DOCK

Edward J. Quirin, Great Neck, N. Y.

Application April 11, 1952, Serial No. 281,726

12 Claims. (Cl. 114—46)

My invention is an improved floating dry dock consisting of transverse sections rigidly connected together to form a pontoon hull and wing walls extending from end to end of the dock along the two sides of the hull.

An important object of my invention is to provide a floating dry dock in sections made of concrete so as to save steel and other metals that may be needed for other purposes. In preferred form the sections are shaped by molding and have interior spaces in the hull to receive water when the dock is to be flooded, and additional enclosed spaces to serve as buoyancy chambers and for locating the machinery to operate the dock.

Another object of my invention is to provide a dock in which the maximum water pressure is kept as low as possible by the use of buoyancy space that is contained in the pontoon hull proper. Generally specially built buoyancy chambers are used for this purpose in the conventional dock, but as the walls of each buoyancy space have to support a much higher pressure than the rest of the structure, the walls thereof need to be made much heavier than the remainder of the dock and the uniformity and continuity of the design is sacrificed to that extent. This in reinforced concrete construction means complicated form work and special reinforcing. The concrete is prestressed throughout.

My invention, therefore, has for a further and special object to enclose the buoyancy space in members of tubular shape made of reinforced concrete, said members being subject to compressive stresses only in withstanding the water pressure from without. For such loading reinforced concrete is admirably adapted and in order not to permit any great bending stresses to occur in the tubular walls, the buoyancy members are preferably run longitudinally through circular openings in the framework of the pontoon part of each section. Said members are disposed at a given distance between their centers and have the required diameter. A relatively low outside water pressure is thus obtained and kept constant for the entire pontoon and the paneling thereof becomes identical throughout the structure and the same forms can be used over and over again. The buoyancy tubes are readily inserted in the pontoons when they are run through the circular openings in the pontoon frames.

My invention has for an object to insure against the reversal of strain in the concrete pontoon, and therefore the buoyancy tubes are placed widely apart on each side of the center bulkhead thereof, so that when the dock is idle with a low pontoon freeboard the pontoon deck is kept in compression, which compression will nicely be intensified when the dock is supporting a ship thereon. It is to be noted in this connection that no extra longitudinal wash bulkheads are needed as the pipes themselves will effectively deaden the sudden water rush from one side to the other under the pontoon.

The nature and advantages of the invention are fully and clearly set forth in the ensuing description and the novel features are pointed out in the appended claims. The drawings show a preferred embodiment of my inven-

2

tion, but changes in various minor respects can be adopted without really altering or omitting any of the essential characteristics.

On the drawings:

Figure 1 is a vertical cross section of half of a floating dry dock according to my invention.

Figure 2 is a horizontal section along the line 2—2 in Figure 1.

Figure 3 is a vertical section on line 3—3 in Figure 1.

Figure 4 is a perspective view of a section of the dock, showing the inside construction.

Figure 5 is a section on line 5—5 of Figure 1; and

Figure 6 shows part of the dock as it appears when the sections are assembled.

The separately built sections of the dry dock are indicated at S in Figure 6, each extending transversely of the dock when the sections are assembled. Each section comprises a pontoon hull 1 with upright walls 2 at its opposite ends. Each pontoon hull 1 has a deck 3 and a bottom 4. With the sections side by side the walls 2 form the wings of the dock, extending along the length thereof at each side of the finished structure, and having inboard and outboard faces or sides 5 and 6 respectively. The hulls and upright walls of the sections are connected so that the walls 2 along each side of the dock are aligned with one another to form the wing walls of the dock, and the decks 3 and bottoms 4 are flush throughout to form the deck and bottom of the dock as a whole. For this purpose I may use the coupling means of any suitable construction.

The sections of the dock are of molded concrete and each section has a vertical bulkhead or partition 7 running lengthwise along the middle, between the deck 3 and bottom 4 at the center of the section. The bulkheads 7 will all be in longitudinal alignment when the dock is completed. In each section there are also transverse bulkheads 8 which intersect the longitudinal bulkhead 7 therein and extend all the way to the outboard sides 6 of the wall 2. Such a dock, for example, may include eight sections, each having a longitudinal bulkhead 7 and, for example, five transverse bulkheads 8 therein, spaced equidistantly apart from one another and from the transverse parallel walls 31 joining the deck 3 and bottom 4 and the extremities of the sides 5 and 6 of the walls 2.

The general construction of each section is illustrated fully in Figure 4, which shows a portion of the lower part of the section in perspective. Mounted in the transverse bulkheads 8 are sealed tubular members 9 which serve as buoyancy chambers, the tubes 9 of each section being closed at their ends by the walls 31 aforesaid. The junction between the top and bottom edges of each bulkhead 7 and the deck 3 and bottom 4 is reinforced by thickened ribs 10 with sides converging towards the bulkhead 7. Between the transverse bulkheads 8 each longitudinal bulkhead 7 is braced and strengthened by vertical reinforcing ribs 11 of similar shape. Also at the top and bottom of the transverse bulkheads 8 are similar ribs 12 joining the bulkheads 8 to the deck 3 and bottom 4; and at the junction of each bulkhead 7 with each transverse bulkhead 8 are reinforcing corners 13. The bulkheads 8 are strengthened by vertical ribs 14, extending from bottom to deck, and between the ribs 14 on the bulkheads 8 extend horizontal beams 15. The ribs 12 are relatively large on both sides of each bulkhead 7 as far as the second rib 14 away from it towards the wings 2, and from there on to the outboard sides 6 the ribs along the top and bottom of the bulkheads 8 are somewhat smaller, as shown at 16.

The tubes 9 are in two tiers, of three each, one tier above the other at each side of the hull; and each tier extends from under the wings towards the central bulkhead 7. The tiers do not reach the bulkhead 7, but termi-

nate at the junctions of the large and small ribs 12 and 16. Sections 8a and 8b of the bulkheads 8 between the bulkhead 7 and the two ribs 14 nearest to the bulkhead 7 on each side of the hull are thus left continuous and imperforate and partly enclose larger spaces to be flooded with water, as will appear later.

The deck 3 and bottom 4 are reinforced on the inner lower faces by longitudinal ribs 17 in the vertical plane of the ribs 14 and the lower parts of the bulkheads 8 have openings 18 so that the spaces under each pair of bulkheads 8 below the chambers 9 are all in communication. The bottom 4 of each section is reinforced, as indicated at 19, at the corner where it is joined to the outboard side 6 of each wall 2, and both deck and bottom are similarly reinforced where they join the walls 31.

Horizontal ribs 20 reinforce each outboard side 6 within the dock at the level of the deck 3, and between the deck and bottom; and these walls are further reinforced by vertical ribs 21 in line with the ribs 16. At the level of the deck the ribs 21 and adjacent ribs 20 are connected to the ribs 16 by ribs 23; and a longitudinal rib 22 within the dock extends along each section at the junction of the deck 3 within the inboard side 5 of the wall 2. The interior of each wall 2 is further reinforced by vertical ribs 24 on both sides 5 and 6 in line with the ribs 23, and joined by horizontal ribs 25 which extend longitudinally of the dock and across the extremities 31 of the walls 2. Near the tops of the walls 2 are floors 26 to support the machinery for pumping and the top of each wall 2 is closed by a roof 27. Both the roof and the lower side of the floor have reinforcing ribs 25 under them at the sides 5 and 6 and extremities 31 and ribs 28 along the middle. The lower ends of the ribs 24 are joined by ribs 29 over the ribs 23.

The deck 3 is convex or crowned slightly, being highest in the middle above the bulkhead 7, as indicated by the line 30 in Figure 1. The walls 31 at the extremities of the walls 2 and along the adjacent faces of the hulls complete the enclosing of the interior of the sections, and the ends of the tubular chambers 9 are sealed in each section by the walls 31. The chambers 9 are buoyancy chambers and the flooding chambers are the spaces surrounding the tubular chambers 9 and between the sections 8a and 8b of the bulkheads 8 up to the bulkhead 7, and within the walls 2 up to the floor 26, in each of the sections.

The tubular members 9 can be molded separately and inserted into openings left in the bulkheads 8 and transverse walls 31 and the opposite ends sealed. Or the walls 31 can be added after the members 9 are mounted in the bulkhead 8. Trap doors can, of course, be placed wherever needed to give access to the interior of the members 9.

Under each member 9 in the lower tier nearest to the bulkhead 7 is a web 32 connecting this member to the bottom 4. This web, when the dock is substantially empty or being pumped out, holds back all water no higher than the lower tier of the members 9; and prevents it, if the dock tilts or rocks, from all collecting near the bulkhead 7 or at one side of the dock. When the dock is being flooded, the water cannot move from side to side till it rises above the level of the member 9 connected to the bottom by this web; but at this stage, sufficient stability is assured.

The concrete throughout is reinforced with steel, in the usual way wherever reinforcement is needed. The entire dock can be of reinforced concrete throughout, or reinforced concrete can be used for the hull only in the separate sections, and steel or wood can be utilized in building the upright walls 2.

Having described my invention, what I believe to be new is:

1. A section for a floating dry dock having a pontoon hull with deck and bottom and a wing wall at each side of the hull, said wing wall being positioned above the deck, a vertical water-tight bulkhead extending longi-

tudinally at the middle of the hull, transverse vertical water-tight bulkheads extending from the longitudinal bulkhead to the sides of the dock beneath said walls, the interior of said wing walls below the top portions thereof 5 communicating with the spaces enclosed by the longitudinal and transverse bulkheads between deck and bottom to form flooding chambers and means forming closed buoyancy chambers supported by the transverse bulkheads in said spaces and above the bottom and below 10 the deck, said buoyancy chambers being disposed in the hull adjacent the wing walls and spaced from said longitudinal bulkhead.

2. A section for a floating dry dock having a pontoon hull with deck and bottom and a wing wall at each side 15 of the hull, said wing wall being positioned above the deck, a vertical longitudinal water-tight bulkhead at the middle of the hull, transverse vertical water-tight bulkheads extending from said longitudinal bulkhead to the sides of the dock beneath said walls, the interior of said 20 wing walls below the top portion thereof and the spaces enclosed by said bulkheads between deck and bottom forming flooding chambers, and means supported by said transverse bulkheads in said spaces and above the bottom and below the deck forming closed tubular buoyancy 25 chambers disposed in said hull adjacent said walls and spaced from said longitudinal bulkhead.

3. A section for a floating dry dock having a pontoon hull with deck and bottom and a wing wall at each side of the hull, said wing wall being positioned above the 30 deck, a vertical longitudinal water-tight bulkhead at the middle of the hull, transverse vertical water-tight bulkheads extending from said longitudinal bulkhead to the sides of the dock beneath said walls, the interior of said wing walls below the top portion thereof and the spaces 35 enclosed by said bulkheads between deck and bottom forming flooding chambers, and means supported by said transverse bulkheads in said spaces and above the bottom and below the deck forming closed tubular buoyancy chambers disposed in said hull adjacent said walls and spaced from said longitudinal bulkhead, said tubular buoyancy chambers being side by side and extending longitudinally of said hull.

4. A section for a floating dry dock having a pontoon hull with deck and bottom and a wing wall at each side 45 of the hull, said wing wall being positioned above the deck, a vertical longitudinal water-tight bulkhead at the middle of the hull, transverse vertical water-tight bulkheads extending from said longitudinal bulkhead to the sides of the dock beneath said walls, the interior of said 50 wing walls below the top portion thereof and the spaces enclosed by said bulkheads between deck and bottom forming flooding chambers, and means supported by said transverse bulkheads in said spaces and above the bottom and below the deck forming closed tubular buoyancy 55 chambers disposed in said hull adjacent said walls and spaced from said longitudinal bulkhead, said tubular buoyancy chambers being disposed side by side in two tiers one above the other and extending longitudinally of said hull.

5. A section for a floating dry dock having a pontoon hull with deck and bottom and a wing wall at each side 60 of the hull, said wing wall being positioned above the deck, a vertical longitudinal water-tight bulkhead at the middle of the hull, transverse vertical water-tight bulkheads extending from said longitudinal bulkhead to the sides of the dock beneath said walls, the interior of said 65 wing walls below the top portion thereof and the spaces enclosed by said bulkheads between deck and bottom forming flooding chambers, and means supported by said transverse bulkheads in said spaces and above the bottom and below the deck forming closed tubular buoyancy 70 chambers disposed in said hull adjacent said walls and spaced from said longitudinal bulkhead, the top portions of said wing walls each having a floor therein extending 75 from the inboard to the outboard sides of said walls.

6. A floating dry dock having a pontoon hull with deck and bottom and a wing wall at each side of the hull above the deck, said dock comprising sections of molded concrete, for connection end to end, each section comprising a part of said hull and wing walls and having walls extending transversely of the dock at the ends closing said parts of the hull and wing walls, a central vertical bulkhead in each section extending lengthwise of said dock, transverse vertical bulkheads in each section joining the central bulkhead to the outboard faces of said wing walls, the interior of the wing walls below the tops in each section forming with said bulkheads in each section, said transverse walls at the ends of each section and said deck and bottom of each section, chambers to be flooded to submerge the dock and means supported by the transverse bulkheads in said chambers between deck and bottom and spaced from said bottom and connected to said transverse walls forming buoyancy chambers in each section, said buoyancy chambers being located adjacent the sides of the dock and spaced from said central bulkheads.

7. A floating dry dock having a pontoon hull with deck and bottom and a wing wall at each side of the hull above the deck, said dock comprising sections of molded concrete, for connection end to end, each section comprising a part of said hull and wing walls and having walls extending transversely of the dock at the ends closing said parts of the hull and wing walls, a central vertical bulkhead in each section extending lengthwise of said dock, transverse vertical bulkheads in each section joining the central bulkhead to the outboard faces of said wing walls, the interior of the wing walls below the tops in each section forming with said bulkheads in each section, said transverse walls at the ends of each section and said deck and bottom of each section, chambers to be flooded to submerge the dock, and means supported by the transverse bulkheads in said chambers between deck and bottom and spaced from said bottom and connected to said transverse walls forming buoyancy chambers in each section, said buoyancy chambers being located adjacent the sides of the dock and spaced from said central bulkheads, said buoyancy chambers being tubular, and same being directly beneath the wing walls.

8. A floating dry dock having a pontoon hull with deck and bottom, and a wing wall at each side of the hull above the deck, said dock comprising sections of molded concrete for connection end to end, each section comprising a part of said hull and wing walls and having walls extending transversely of the dock at the ends closing said parts of the hull and wing walls, a central vertical bulkhead in each section extending lengthwise of said dock, transverse vertical bulkheads in each section joining the central bulkhead to the outboard faces of said wing walls, the interior of the wing walls below the tops in each section forming with said bulkheads in each section, said transverse walls at the ends of each section and said deck and bottom of each section, chambers to be flooded to submerge the dock, and means supported by the transverse bulkheads in said chambers between deck and bottom and spaced from said bottom and connected to said transverse walls forming buoyancy chambers in each section, said buoyancy chambers being located adjacent the sides of the dock and spaced from said central bulkheads, said buoyancy chambers being tubular and extending longitudinally of the dock from one of said transverse walls to the other and closed at their opposite ends.

9. A floating dry dock having a pontoon hull with deck and bottom and a wing wall at each side of the hull above the deck, said dock comprising sections of molded concrete for connection end to end, each section comprising a part of said hull and wing walls and having walls extending transversely of the dock at the ends closing said parts of the hull and wing walls, a central vertical bulkhead in each section extending lengthwise

of said dock, transverse vertical bulkheads in each section joining the central bulkhead to the outboard faces of said wing walls, the interior of the wing walls below the tops in each section forming with said bulkheads in each section, said transverse walls at the end of each section and said deck and bottom of each section, chambers to be flooded to submerge the dock, and means supported by the transverse bulkheads in said chambers between deck and bottom and spaced from said bottom and connected to said transverse walls forming buoyancy chambers in each section, said buoyancy chambers being located adjacent the sides of the dock and spaced from said central bulkheads, said buoyancy chambers being tubular and arranged in two tiers, one above the other, in the hull.

10. A floating dry dock having a pontoon hull with deck and bottom and a wing wall at each side of the hull above the deck, said dock comprising sections of molded concrete for connection end to end, each section
20 comprising a part of said hull and wing walls and having walls extending transversely of the dock at the ends closing said parts of the hull and wing walls, a central vertical bulkhead in each section extending lengthwise of said dock, transverse vertical bulkheads in each
25 section joining the central bulkhead to the outboard faces of said wing walls, the interior of the wing walls below the tops in each section forming with said bulkheads in each section, said transverse walls at the ends of each section and said deck and bottom of each section, chambers to be flooded to submerge the dock, and means supported by the transverse bulkheads in said chambers between deck and bottom and spaced from said bottom and connected to said transverse walls forming buoyancy chambers in each section, said buoyancy chambers being
30 located adjacent the sides of the dock and spaced from said central bulkheads, the top portions of the parts of
35 the wings of each section having floors therein.

40 11. A floating dry dock having a pontoon hull with
deck and bottom and a wing wall at each side of the hull
above the deck, said dock comprising sections of molded
concrete for connection end to end, each section comprising
a part of said hull and wing walls and having
walls extending transversely of the dock at the ends
closing said parts of the hull and wing walls, a central
45 vertical bulkhead in each section extending lengthwise
of said dock, transverse vertical bulkheads in each section
joining the central bulkhead to the outboard faces
of said wing walls, the interior of the wing walls below
the tops in each section forming with said bulkheads
50 in each section, said transverse walls at the ends of each
section and said deck and bottom of each section, chambers
to be flooded to submerge the dock and means
supported by the transverse bulkheads in said chambers
between deck and bottom and spaced from said bottom
55 and connected to said transverse walls forming buoyancy
chambers in each section, said buoyancy chambers being
located adjacent the sides of the dock and spaced from
said central bulkheads, each section having horizontal
brace beams connecting the transverse bulkheads.

60 12. A floating dry dock having a pontoon hull with
deck and bottom and a wing wall at each side of the
hull above the deck, said dock comprising sections of
molded concrete for connection end to end, each section
comprising a part of said hull and wing walls and having
65 walls extending transversely of the dock at the ends
closing said parts of the hull and wing walls, a central
vertical bulkhead in each section extending lengthwise
of said dock, transverse vertical bulkheads in each section
joining the central bulkhead to the outboard faces of
70 said wing walls, the interior of the wing walls below
the tops in each section forming with said bulkheads in
each section, said transverse walls at the ends of each
section, and said deck and bottom of each section, cham-
bers to be flooded to submerge the dock, and means
75 supported by the transverse bulkheads in said chambers

between deck and bottom and spaced from said bottom and connected to said transverse walls forming buoyancy chambers in each section, said buoyancy chambers being located adjacent the sides of the dock and spaced from said central bulkheads, each section having horizontal brace beams connecting the transverse bulkheads, said

transverse bulkheads having vertical ribs to which said beams are joined.
